UNITED STATES PATENT OFFICE

MAX SCHLING, OF SCARSDALE, NEW YORK

DESIGN FOR A FLOWERPOT

Application filed October 29, 1930. Serial No. 37,431. Term of patent 3½ years.

To all whom it may concern:

Be it known that I, MAX SCHLING, a citizen of the United States, residing at 9 Richbell Road, Scarsdale, in the county of Westchester and State of New York, have invented a new, original, and ornamental Design for Flower Pots, of which the following is a specification, reference being had to the accompanying drawing, forming part thereof. The figure is a perspective view of a flower pot showing my new design. The article herein described is circular in shape. The flowers, the candle-holder, and the candle, are integral parts of the flower pot.

I claim:

The ornamental design for a flower pot, as shown and described.

In testimony whereof I affix my signature.

MAX SCHLING.
